James R. Hyde, of Troy, N.Y.
Letters Patent No. 1079. Dated Jan 18. 1859.

The schedule referred to in these Letters Patent, and making part of the same.

To all whom it may concern

Be it known that I, James R. Hyde, of the City of Troy, in the County of Rensselaer, and State of New York, have invented or produced a new and original Design for a Cooking Stove, which I call the "Arbiter"; and I do hereby declare that the following is a full, clear, and exact description of the same, reference being had to the annexed drawings making a part of this specification, in which

Fig. 1. is a front and

Fig. 2. a side view of the stove.

The same letters refer to like parts in both figures.

Each upper door, A. A', of the front of the stove has the ornamental vine, a, surrounding the check work ground, b.

Each lower door, B. B', of the front has the ornamental vine, a, surrounded by the check work ground, b. The front plate, C, has, between the upper and lower doors, the vine-like ornament, c, upon the plaid check ground, d. - The oven doors, D. D', of the side of the stove have the ornamented vines, e. e', surrounding the check ground f. f'. - The side plate, E, has a row of the ornament, g, along its top, the plaid check ornamental molding, h, along its bottom, and the plaid check ground, i, surrounded by the ornamented

molding, j, along its front. - And the foot, F, has the rosette K with a checkered center l on its upper part, and the checkered leaf m on its lower part.

What I claim as my invention and desire to secure by Letters Patent is
ornamenting the doors, front-plate, side-plates and foot of cooking stoves as herein specified
and represented in the annexed photographic drawings.
